UNITED STATES PATENT OFFICE

2,417,834

SELF-PULSING OSCILLATOR

Harold W. Lord, Schenectady, N. Y., assignor to
General Electric Company, a corporation of
New York

Application February 19, 1943, Serial No. 476,371

13 Claims. (Cl. 250—36)

1

This invention relates to pulse generating circuits, particularly to such circuits for use in connection with pulse transmitters and the like, and its object is to provide improved and efficient circuits of this character which are extremely simple in form and at the same time capable of producing pulses of considerable power.

In accordance with my invention, a self-pulsing oscillating circuit is provided constituted essentially by a single electron discharge device arranged not only as an oscillator but also to feed back or supply energy from its anode-cathode circuit to its control electrode-cathode circuit through a transformer and a pulse forming element, such as a transmission line section, connected in the control electrode-cathode circuit for determining the duration and shape of the pulse. My invention permits the operation of a self-pulsing oscillator in which the power required for pulsing is only a fraction of the total input power.

The features of my invention which I believe to be novel are set forth with particularity in the appended claims. My invention itself, both as to its organization and manner of operation, together with further objects and advantages thereof may best be understood by reference to the following description taken in connection with the accompanying drawing in which the single figure is a diagrammatic representation of a self-pulsing oscillator circuit embodying my invention.

The oscillator circuit illustrated in the drawing comprises an electron discharge device 10 having an anode 11, a cathode 12 and a control electrode 13. In order to produce oscillations and to determine the frequency of the oscillations there is provided a tunable circuit of any desired type. In the drawing there is illustrated a modified Hartley oscillatory circuit comprising the inductances 15 and 16 connected by a pair of series connected radio frequency bypass condensers. The condensers prevent radio frequency currents from flowing through the pulsing circuit. The combination of coils and condensers is shunted by a variable condenser 18. One side of the circuit 14 is connected to the anode 11 and the other side of the tunable circuit is connected to the control electrode 13. The midpoint between the condensers 17 is grounded. Any suitable bias for the discharge device may be used as, for example, the resistance 19 between the cathode 12 and ground. Anode potential is supplied from a suitable source, indicated by the plus and minus signs in the drawing. The circuit oscillates in a well known manner, the coupling between the

2

anode-to-cathode and control electrode-to-cathode circuits being sufficient to provide feedback.

The pulse generating circuit comprises the electron discharge device 10 and also a transformer 20, having windings 21 and 22, respectively, in shunt with the oscillator anode-cathode circuit and the oscillator control electrode-cathode circuit, respectively, the winding 22 being oppositely poled with respect to the winding 21. 5 A condenser 23 is connected in series with the winding 21 and is of such a capacity as to provide a substantially open circuit for direct currents but present substantially no impedance to pulse frequency currents. The pulse generating circuit is preferably connected to a suitable direct current source through an inductance 24. The transformer 21 may also comprise a third winding 25, to the terminals of which any desired source of synchronizing pulses may be connected.

A pulse forming and pulse determining element 26 is connected in series with the transformer winding 22 and a resistor 27 in a second control electrode-cathode circuit of the discharge device 10. The element 26 is a capacitive time delay network and preferably comprises a suitable transmission line section, the line section including a plurality of capacitors 28 and reactances 29. The time element characteristics of such networks are well known to those skilled in the art.

In operation of the circuit illustrated in the drawing, let it be assumed that the circuit is not oscillating but that a small current is beginning to flow in the anode-cathode circuit of the discharge device 10. Under this condition small potentials appear across the windings of pulse transformer 20 in the second anode-cathode circuit. By properly connecting the secondary winding 22, a positive potential is impressed upon the control electrode 13 of the discharge device 10 and thereby causes more anode current to flow which in turn produces more current in the winding 21 and therefore more potential is impressed upon control electrode 13 from winding 22. This regenerative action continues at a very rapid rate.

During the above described regenerative action, a portion of the anode supply potential appears across the transformer primary winding 21 and a corresponding positive potential is impressed by secondary winding 22 upon the control electrode circuit. Nearly all of the positive potential thereon appears across resistor 27 and the pulse forming line 26. If the resistance of

resistor 27 plus the equivalent control electrode-to-cathode resistance of the discharge device 10 is equal to the surge impedance of the transmission line 26, then half of the secondary voltage of the winding 22 appears across the transmission line 26 and half across the resistor 27 and the control electrode-to-cathode resistance of the discharge device 10.

The potential thus impressed upon the transmission line 26 causes a wave to travel down the line which is reflected at the open end of the line and travels back to the starting end thereof in proper phase so that as the wave finishes its travel a voltage equal to all of the voltage applied by the secondary winding 22 across the transmission line 26 and the resistance loads constituted by the resistor 27 and the control electrode-to-cathode resistance, appears across the line 26 in the form of a charge on each capacitor 28, of such polarity that a negative potential appears on the control electrode side of the line. Under this condition the potential upon control electrode 13 is reduced substantially to zero. The resulting increase in the anode circuit impedance of discharge device 10 reduces the potential across the primary winding 21 and this decrease, through regenerative action, increases, in turn, the negative potential applied to the control electrode 13 from winding 22 until the discharge device is biased to and beyond cut-off, thus terminating the pulse.

It may be preferable to so proportion the transmission line 26 and the resistance 27 that slightly more voltage develops across the line than across the resistor in which case a negative voltage is reflected back and a more negative potential is applied to the control electrode.

At the end of the pulse the charge on the capacitors leaks off at a rate determined by the leak resistor 30 until the negative bias upon the control electrode 13 is sufficiently reduced so that when a synchronizing potential is applied to the control electrode-cathode circuit another pulse will be initiated. The pulse cycle as above described may then be repeated indefinitely.

If it is desired that the pulse generating circuit be operated in a self-timing manner, the ungrounded end of the leak resistor 30 may be connected directly to the cathode 12 and the synchronizing source omitted, the pulse rate then being determined by adjustment of the resistor 30.

The above described pulse generating circuit is substantially the same as that described and claimed in my copending application, S. N. 464,033, filed Oct. 31, 1942, and assigned to the same assignee as the present invention.

If the regenerative action of the pulse generating circuit is allowed to continue until the discharge device is driven to saturation a relatively low anode potential results. In order to maintain the anode potential sufficient for satisfactory oscillatory conditions in the oscillator portion of the circuit, there is connected a voltage limiting discharge device, such, for example, as a glow tube 31, in shunt with the primary winding 21 of the transformer 20 and designed to break down at a predetermined voltage which is sufficient to form pulses but which will maintain the anode potential at a potential different from the source of potential only by the amount required to produce satisfactory pulses. Accordingly, a greater current is conducted through the discharge device than if the anode potential is allowed to drift lower.

The regenerative action above described may also cause a considerable control electrode current to flow. In order to maintain the control electrode at a potential satisfactory for good oscillation it is necessary to provide means to insure that regeneration will not raise the control electrode potential sufficiently to cause appreciable control electrode current to flow. For this purpose, there is provided means for limiting the control electrode voltage. In the illustrative form of my invention, this means takes the form of a unilateral device, such as a diode 32, the anode of which is connected to the control electrode end of the resistance 27 and the cathode of which is connected to the cathode 12. The cathode of the diode 32 is grounded for pulse frequency currents by a suitable condenser 33.

With the foregoing arrangement there is provided ample anode voltage and the correct control electrode voltage to insure oscillation during pulses.

The energy for blocking the control electrode circuit in order to terminate pulses, as described above, is supplied from the anode-cathode circuit to the control electrode-cathode circuit through the pulse forming network 26 which is entirely independent of the oscillator part of the circuit. In the usual pulse transmission system the repetition rate of the pulses is substantially different, usually many times less, than the frequency of the oscillating circuit. Hence the oscillator adjustments may be made independently of the pulsing adjustments. The reverse is also true, for the circuit will function as a pulser with the oscillator portion inoperative. This independence of pulsing circuit with respect to the oscillating circuit permits determination of the pulse width and the repetition rate of the pulsing circuit without regard to the oscillator adjustments and the shape of the pulse output from the oscillator is controllable by the pulsing elements of the circuit.

While I have shown and described a particular embodiment of my invention, it will be obvious to those skilled in the art that changes and modifications may be made without departing from my invention in its broader aspects. For example, the cathode of the diode 32 may be grounded or connected to ground through a variable resistance shunted by a condenser of such a capacity as to constitute a ground for pulse frequency currents. I, therefore, aim in the appended claims to cover all such changes and modifications as fall within the true spirit and scope of my invention.

What I claim as new and desire to secure by Letters Patent of the United States is:

1. In combination, a direct current source, an oscillator circuit energized therefrom comprising an electron discharge device having an anode, a cathode, and a control electrode, said oscillator including an anode-cathode circuit for said discharge device and means for deriving from said anode-cathode circuit and supplying to said control electrode oscillatory energy in proper phase relation to support oscillations in said circuit, a pulse generating circuit energized from said source and including said discharge device, a circuit connected between said control electrode and said cathode, a second circuit connected between said anode and said cathode, regenerative means including a transformer having a secondary winding and a primary winding operatively associated with said last-named circuits, respectively, for supplying potentials from said second anode-

cathode circuit to said control electrode-cathode circuit, and voltage limiting means in shunt with said transformer primary winding for maintaining a relatively high potential on said anode during each pulse.

2. In combination, a direct current source, an oscillator circuit energized therefrom comprising an electron discharge device having an anode, a cathode, and a control electrode, said oscillator including an anode-cathode circuit for said discharge device and means for deriving from said anode-cathode circuit and supplying to said control electrode oscillatory energy in proper phase relation to support oscillations in said circuit, a pulse generating circuit energized from said source and including said discharge device, said pulse generating circuit comprising a circuit connected between said control electrode and said cathode and a second circuit connected between said anode and said cathode, regenerative means including a transformer coupling said last-named circuits thereby to supply potentials from said second anode-cathode circuit to said control electrode-cathode circuit during each pulse period, and electric discharge means for limiting the control electrode-cathode voltage to a value which substantially prevents the flow of control electrode current due to pulse voltages.

3. In combination, a direct current source, an oscillator circuit energized therefrom comprising an electron discharge device having an anode, a cathode, and a control electrode, said oscillatory circuit including an anode-cathode circuit for said discharge device and means for deriving from said anode-cathode circuit and supplying to said control electrode oscillatory energy in proper phase relation to support oscillations in said circuit, a pulse generating circuit energized from said source and including said discharge device, said pulse generating circuit comprising a circuit connected between said control electrode and said cathode and a second circuit connected between said anode and said cathode, regenerative means including a transformer having a secondary winding and a primary winding operatively associated with said last-named circuits, respectively, thereby to supply potentials from said second anode-cathode circuit to said control electrode-cathode circuit, discharge means for limiting the control electrode-cathode voltage substantially to prevent the flow of control electrode current due to pulse voltages, and second discharge means for limiting the voltage across said primary winding to a predetermined value whereby the anode potential remains sufficiently high during pulse periods to maintain oscillations in said oscillator.

4. In combination, a direct current source, an oscillator circuit energized therefrom comprising an electron discharge device having an anode, a cathode, and a control electrode, said oscillator including an anode-cathode circuit for said discharge device and means for deriving from said anode-cathode circuit and supplying to said control electrode oscillatory energy in proper phase relation to support oscillations in said circuit, a pulse generating circuit energized from said source and including said discharge device, a circuit connected between said control electrode and said cathode and a second circuit connected between said anode and said cathode, regenerative means including a transformer operatively associated with said last-named circuits for supplying potentials from said second anode-cathode circuit to said control electrode-cathode

circuit during each pulse period, and means for limiting the control electrode-cathode voltage to substantially prevent the flow of control electrode current due to pulse voltages, said last mentioned means comprising unilateral means connected between said control electrode and said cathode.

5. In combination, a direct current source, an oscillator circuit energized therefrom comprising an electron discharge device having an anode, a cathode, and a control electrode, said oscillator including an anode-cathode circuit for said discharge device and means for deriving from said anode-cathode circuit and supplying to said control electrode oscillatory energy in proper phase relation to support oscillations in said circuit, a pulse generating circuit energized from said source and including said discharge device, said pulse generating circuit comprising an open-ended transmission line section connected between said control electrode and said cathode and a second circuit connected between said anode and said cathode, and a transformer regeneratively coupling said second circuit to said control electrode through said transmission line section thereby rapidly to build up oscillations in said discharge device upon initiation of conduction and abruptly to render said discharge device non-conductive upon reflection by said transmission line of pulses applied through said transformer.

6. In combination, a direct current source, an oscillator circuit energized therefrom comprising an electron discharge device having an anode, a cathode, and a control electrode, said oscillator including an anode-cathode circuit for said discharge device and means for deriving from said anode-cathode circuit and supplying to said control electrode oscillatory energy in proper phase relation to support oscillations in said circuit, a non-oscillatory square wave pulse generating circuit energized from said source and including said discharge device, said pulse generating circuit comprising an open-ended transmission line section connected in series with a resistor between said control electrode and said cathode and a second circuit connected between said anode and said cathode, and a transformer regeneratively coupling said second anode-cathode circuit to said control electrode through said transmission line section, said coupling being so poled that upon initiation of oscillations in said discharge device said transformer applies a positive pulse to said control electrode, said transmission line section reflecting said positive pulse in aiding phase relation thereby to apply a delayed negative potential to said control electrode and render said discharge device non-conductive.

7. In combination, a direct current source, an oscillator energized from said source and comprising an electron discharge device having an anode, a cathode and a control electrode, an anode-cathode circuit for said discharge device and means for deriving from said anode-cathode circuit and supplying to said control electrode oscillatory energy in proper phase relation to support oscillations in said circuit, and a pulse generating circuit energized from said direct current source in parallel circuit relation with said anode-cathode circuit, said pulse generating circuit including a capacitive time delay network connected to control the potential of said control electrode, thereby recurrently to render said discharge device conductive to generate oscillations at a repetition rate independent of the frequency of said generated oscillations.

8. In combination, a direct current source, an

oscillator energized from said source and comprising an electron discharge device having an anode, a cathode and a control electrode, an anode-cathode circuit for said discharge device, oscillator coupling means for deriving from said anode-cathode circuit and supplying to said control electrode oscillatory energy in proper phase relation to support oscillations in said circuit, regenerative coupling means between said control electrode and said anode-cathode circuit independent of said oscillator coupling means, and a capacitive time delay network energized by said regenerative coupling means and coupled to said control electrode for rendering said discharge device non-conductive a predetermined time after initiation of oscillations therein and independent of the frequency of said oscillations.

9. In combination, a direct current source, an oscillator energized from said source and comprising an electron discharge device having an anode, a cathode and a control electrode, an anode-cathode circuit for said discharge device, oscillator coupling means for deriving from said anode-cathode circuit and supplying to said control electrode oscillatory energy in proper phase relation to support oscillations in said circuit, regenerative coupling means between said anode-cathode circuit and said control electrode independent of said oscillator coupling means, and a capacitive time delay network coupled to said control electrode and responsive to energization of said regenerative coupling means by initiation of oscillations in said discharge device for rendering said discharge device non-conductive a predetermined time after initiation of said oscillations.

10. In combination, a direct current source, an oscillator energized from said source and comprising an electron discharge device having an anode, a cathode and a control electrode, an anode-cathode circuit for said discharge device, oscillator coupling means for deriving from said anode-cathode circuit and supplying to said control electrode oscillatory energy in proper phase relation to support oscillations in said circuit, and regenerative coupling means between said control electrode and said anode-cathode circuit independent of said oscillator coupling means, a capacitive time delay network energized by said regenerative coupling means and coupled to said control electrode for rendering said discharge device non-conductive a predetermined time after initiation of oscillations therein, and means for discharging said capacitive network, thereby to render said discharge device conductive a predetermined time after termination of conduction.

11. In combination, a direct current source, an oscillator energized from said source and comprising an electron discharge device having an anode, a cathode and a control electrode, an anode-cathode circuit for said discharge device, oscillator coupling means for deriving from said anode-cathode circuit and supplying to said control electrode oscillatory energy in proper phase relation to support oscillations in said circuit, regenerative coupling means between said anode-cathode circuit and said control electrode independent of said oscillator coupling means, a non-oscillatory capacitive pulse forming network cou-

pled to said control electrode and responsive to energization of said regenerative coupling means for rendering said discharge device non-conductive a predetermined time after initiation of oscillations therein, discharge means for said capacitive network arranged to render said discharge device conductive a predetermined time after termination of conduction, and means coupled to said control electrode for recurrently rendering said discharge device conductive.

10 12. In combination, a direct current source, an oscillator energized from said source and comprising an electron discharge device having an anode, a cathode and a control electrode, an anode-cathode circuit for said discharge device, oscillator coupling means for deriving from said anode-cathode circuit and supplying to said control electrode oscillatory energy in proper phase relation to support oscillations in said circuit, regenerative coupling means independent of said oscillator coupling means and including an open-ended transmission line section connected between said anode-cathode circuit and said control electrode, said transmission line being arranged by reflection to render said discharge device non-conductive a predetermined time after initiation of oscillations therein and independent of the frequency of said oscillations, discharge means for said transmission line arranged to render said discharge device conductive a predetermined time after termination of conduction, and timing means coupled to said regenerative means for recurrently rendering said discharge device conductive at a repetition rate independent of the period of oscillation.

15 13. In combination, a direct current source, an oscillator energized therefrom comprising an electron discharge device having an anode, a cathode, and a control electrode, said oscillator including an anode-cathode circuit for said discharge device and means for deriving from said anode-cathode circuit and supplying to said control electrode oscillatory energy in proper phase relation to support oscillations in said circuit, pulse generating means energized from said source and including a second circuit connected between said anode and cathode and a capacitive time delay network connected between said cathode and said control electrode, and means for coupling said second circuit and said time delay network, thereby to render said discharge device non-conductive a predetermined time after initiation of oscillations therein.
